UNITED STATES PATENT OFFICE.

MORTIMER M. SHACKITT, OF BROOKLYN, NEW YORK.

CAN.

Application filed December 9, 1920. Serial No. 429,491.

To all whom it may concern:

Be it known that I, MORTIMER M. SHACKITT, a citizen of the United States, and resident of the city of New York, borough of Brooklyn, in the county of Kings and State of New York, have invented a new and Improved Can, of which the following is a full, clear, and exact description.

The invention relates to metallic shipping and storing vessels, and its object is to provide a new and improved can more especially designed for household use for storing ashes, kitchen refuse, and the like, and arranged to provide an exceedingly strong and durable can capable of withstanding the rough handling to which cans of this type are subjected particularly when emptying the same.

Another object is to permit the user to readily place the ashes or refuse into the can without removing the cover from the can.

Another object is to keep the can normally closed to prevent undesirable odors from escaping from the can into the kitchen or other place in which the can is usually located.

Another object is to hold the can securely in closed position against accidental displacement and to allow convenient removal of the cover whenever it is desired to empty the can.

Another object is to permit of taking a firm hold of the can for moving it about and handling it when emptying the contents of the can into a removal wagon or cart.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a sectional side elevation of the improved can;

Figure 2 is an inverted plan view of the same;

Figure 3 is a plan view of the same with parts broken out;

Figure 4 is an enlarged cross section of the filling door in the can cover;

Figure 5 is a sectional side elevation of the same on the line 5—5 of Figure 4;

Figure 6 is an enlarged sectional side elevation of the upper end of the improved can

and showing more particularly one of the locking devices for locking the cover to the can body, the section being on the line 6—6 of Figure 3; and

Figure 7 is an enlarged face view of one of the carrying handles on the side of the can.

The body 10 of the can is preferably made of sheet metal and circular in shape, and the lower end of the can body is permanently

closed by a sheet metal bottom 11 having a downwardly extending flange 12 fitting against the inner face of the lower portion of the body 10.

In order to reinforce the lower end of the can body 10 and the bottom 11 use is made of a reinforcing ring 15 and a hoop 16, of which the reinforcing ring 15 is made of angle iron having its horizontal member 17 fitting against the under side of the bottom 11 and having its vertical member 18 fitting against the inner

face of the bottom flange 12. The reinforcing hoop 16 fits onto the outer surface of the lower portion of the can body opposite the flange 12 and the vertical member 18

of the reinforcing ring 15. Rivets 19 or other fastening means are used to fasten the vertical member 18, the flange 12, the lower portion of the can body 10 and the hoop 16 together by passing the rivet shanks through

the said parts, as plainly shown in Figure 1. The upper end of the can body 10 is reinforced exteriorly by a hoop 20 of angle iron having its vertical member 21 fitting exteriorly on the upper end of the can body 10, and having its horizontal member 22 extending outwardly. The vertical member 21 of the reinforcing hoop 20 is fastened to the upper end of the can body 10 by rivets 23 or other fastening devices. The can body is reinforced intermediate the top and bottom by spaced pressed out ribs 25 extending vertically from near the bottom 11 to within a short distance of the top of the can body 10, as plainly shown in Figure 1. The can body 10 is further reinforced by bars 26

preferably of flat iron and extending vertically on the outer face of the can body at the sides thereof. The reinforcing bars 26 are preferably located between adjacent ribs 25.

The lower ends 27 of the bars 26 are bent outwardly and overlie the lower hoop 16 to which the said lower ends 27 are fastened by the rivets 19, previously mentioned.

The upper ends 28 of the reinforcing bars 26 are likewise bent outward and extend through slots 29 formed in the horizontal

member 22 of the upper hoop 20. The upper ends 29 fit onto the outside of the vertical member 21 of the upper hoop 29 and are fastened thereto by rivets 23 previously mentioned. The reinforcing bars 26 are fastened to the body 10 intermediate the upper and lower ends by rivets 30 or similar fastening devices.

From the foregoing it will be seen that 10 the can body is strongly reinforced circumferentially both at the bottom and the top, and is likewise reinforced vertically by the integral ribs 25 and the reinforcing bars 26 which fit onto the can body 10 and connect 15 the lower and upper hoops 16 and 20 with each other. The strongly reinforced bottom of the can permits of conveniently rolling the filled can along a pavement or other surface while in tilted position. By providing the 20 integral ribs 25 and the vertical reinforcing bars 26 the body is not liable to be dented when emptying the contents of the can in an ash cart.

The upper open end of the can body 10 is 25 normally closed by a cover 40 provided at or near its middle with a filling door 41. The cover 40 is provided with a depending flange 42 fitting exteriorly onto the upper end of the can body and being seated on the horizontal member 22 of the upper hoop 20. The flange 42 of the cover 40 is provided at 30 diametrically opposite points with angular brackets 43 (see Figure 6), each provided with a depending stud or pin 44 having a 35 head 45 and adapted to engage a keyhole 46 (see Figure 3) formed in the horizontal member 22 of the upper hoop 20. It is understood that the head 45 of the pin or stud 44 readily passes through the enlarged end 40 of the keyhole slot 46, and by then slightly turning the cover 40 the stud passes into the narrow portion of the keyhole slot 46 with the head 45 abutting against the under side of the horizontal member 22 of the hoop 20 45 to lock the cover 40 to the said horizontal member. Thus the cover 40 is normally locked in place on the upper end of the can to close the same and whenever it is desired to empty the can of its contents the cover 50 can be readily unlocked and removed by turning the cover 40 in the reverse direction until the heads 45 register with the enlarged ends of the keyhole slots 46 to allow of lifting the cover off the can. The cover 40 is 55 provided on the top with suitable handles 47 to permit of conveniently manipulating the cover in placing it in position on the can or removing it therefrom as above explained.

The filling door 41 is connected by a hinge 60 50 with a depending annular flange 51 formed centrally on the cover 40, the flange 51 terminating at its lower end in an inwardly extending rim 52 thus providing an opening 53 for the passage of ashes, kitchen 65 refuse and the like passed into the can at the

time the door 41 is swung upward into open position, as indicated in dotted lines in Figure 1. The door 41 is normally held closed by a torsion spring 55 mounted on the pintle of the hinge 50 and connected at one end to 70 the door 41 and at the other end to the cover 40 (see Figures 3 and 5). It is understood that when the door 41 is swung into open position the spring 55 is compressed and hence when the door is released by the user 75 it swings shut by the action of the spring 55. The door is provided near its free end with a handle 56 to permit of conveniently swinging the door into open position. The door is preferably provided with a depending 80 flange 57 to reinforce the door, the said flange fitting against the depending flange 51 of the cover, and the said flange is in close proximity to the flange 52 to provide a tight joint between the door and the cover. 85

In order to permit of conveniently carrying the can about or lifting it, use is made of handles 60, preferably of inverted T-shape and pivoted at 61 on brackets 62 fastened by rivets 63 to the outer faces of 90 the reinforcing bars 26, the said rivets also aiding in fastening the reinforcing bars 26 to the can body 10, as will be readily understood by reference to Figure 1. The handles 60 are provided at their fulcrumed ends with 95 annular heels 64 adapted to abut against the brackets 62 on swinging the handle 60 upward into an approximately horizontal position when carrying the can about or lifting it. It will be noticed that the handles 60 normally hang downward and when swung into horizontal position they afford a firm hold for a person, without danger of the hands becoming cramped, as is so frequently the case on gripping the small ring-shaped 100 handles now generally on cans of this type. It will also be noticed that by mounting the handles 60 on brackets 62 attached to the reinforcing bars 26, the body of the can is 105 not liable to be injured by the strain incident to lifting a filled can. 110

Having thus described my invention, I claim as new and desire to secure by Letters Patent:—

1. In a can, a can body, a bottom having an angular flange fitting against the inner face of the said body at the lower end thereof, an angle iron reinforcing ring fitting against the under side of the said bottom and its flange, a lower encircling hoop encircling the lower end of the said can body, an upper hoop of angle iron engaging the upper end of the said can body and having its horizontal member extending outwardly, vertical reinforcing bars extending exteriorly on the said body and engaging the said hoops, means fastening the lower ends of the said can body and reinforcing bars, the said lower hoop, the bottom flange and the angle iron reinforcing ring together, and means fas- 115 120 125 130

tening the upper hoop, the upper end of the can body and the reinforcing bars together.

2. In a can, a can body, a bottom having an angular flange fitting against the inner face of the said body at the lower end thereof, an angle iron reinforcing ring fitting against the under side of the said bottom and its flange, a lower encircling hoop encircling the lower end of the said can body, an upper hoop of angle iron engaging the upper end of the said can body and having its horizontal member extending outwardly, the said upper hoop having slots in its horizontal member, and vertical reinforcing bars extending exteriorly on the said can body and having its lower end overlying the said lower hoop and having its upper end extending through the said slots of the upper hoop.
3. In a can, a can body, a hoop of angle iron engaging the upper end of said body and having its horizontal member extending outwardly, said hoop having a slot through its horizontal member, and a vertical reinforcing bar extending exteriorly on the said can body and having its upper end extending through the slot of the said hoop.
4. In a can, a can body, a bottom having an angular flange fitting against the inner face of the said body at the lower end thereof, an angle iron reinforcing ring fitting against the under side of the said bottom and its flange, a lower encircling hoop encircling the lower end of the said can body, an upper hoop of angle iron engaging the upper end of the said can body and having its horizontal member extending outwardly, vertical reinforcing bars extending exteriorly on the said body and engaging the said hoops, means fastening the lower ends of the said can body and reinforcing bars, the said lower hoop, the bottom flange and the angle iron

reinforcing ring together, means fastening the upper hoop, the upper end of the can body and the reinforcing bars together, and a cover having a depending flange fitting over the said vertical member of the said upper hoop.

5. In a can, a can body open at its upper end, a cover for the can body, said cover having an opening provided with a depending flange, said flange terminating at its lower end in an inwardly extending rim, and a spring-pressed door mounted on said cover for closing said opening, said door having a perimetric depending flange adapted to fit within the flange of said cover in sliding contact therewith and to rest upon the inwardly extending rim portions of the latter when said door is in closed position.

6. In a can, a can body, a lower encircling hoop encircling said can body at its lower end, an upper reinforcing hoop encircling the can body at its upper end, vertical reinforcing bars extending exteriorly on the said body and engaging the said hoops, means fastening the lower end of the said can body, the reinforcing bars and the said lower hoop together, means fastening the upper hoop, the upper end of the can body and the reinforcing bars together, and pivoted handles mounted on certain of the vertical reinforcing bars and attached both to said bars and to the can body.

7. In a can, a can body, and T-shaped handles pivotally attached at the ends of the stems thereof to said can body, said handles being formed at their pivoted ends to coact with said can body to prevent further upward movement of the handles when the latter have been swung into an approximately horizontal position.

MORTIMER M. SHACKITT.
